US00D738208S

(12) **United States Design Patent**
Diehl et al.

(10) **Patent No.:** **US D738,208 S**
(45) **Date of Patent:** **** Sep. 8, 2015**

(54) **PACKAGE FOR FOOD PRODUCT**

(71) Applicant: **Kraft Foods Group Brands LLC**,
Northfield, IL (US)

(72) Inventors: **Paul F. Diehl**, Brooklyn, NY (US);
Graham C. Hufton, New York, NY
(US); **Aaron P. Burghard**, Chicago, IL
(US); **Strom R. Strandell**, Chicago, IL
(US)

(73) Assignee: **Kraft Foods Group Brands LLC**,
Northfield, IL (US)

(**) Term: **14 Years**

(21) Appl. No.: **29/446,326**

(22) Filed: **Feb. 22, 2013**

(51) LOC (10) Cl. **09-03**

(52) U.S. Cl.

(57) **CLAIM**

We claim the ornamental design for a package for food product, as shown and described.

DESCRIPTION

FIG. 1 is a front perspective view of a package for food product of our new design;

FIG. 2 is a top view thereof;

FIG. 3 is a bottom view thereof;

FIG. 4 is a front view thereof;

FIG. 5 is a back view thereof;

FIG. 6 is a right side thereof view; and,

FIG. 7 is a left side view thereof.

The broken line portion of the figure drawings is included to show unclaimed subject matter only and forms no part of the claimed design.

1 Claim, 5 Drawing Sheets
